UNITED STATES PATENT OFFICE.

FRANK X. SANDT, OF KENOSHA, WISCONSIN.

SUSPENDED BAG.

1,207,638.

Specification of Letters Patent.

Patented Dec. 5, 1916.

Application filed February 23, 1916. Serial No. 79,885.

To all whom it may concern:

Be it known that I, FRANK X. SANDT, a citizen of the United States, residing at Kenosha, in the county of Kenosha and 5 State of Wisconsin, have invented certain new and useful Improvements in Suspended Bags, of which the following is a specification.

The object of this invention is to produce 10 a bag, as, for example, a laundry bag, having means whereby it may be conveniently suspended, opened and closed.

In the accompanying drawings, Figure 1 is a perspective view of a bag embodying 15 my invention. Fig. 2 is a cross-sectional view of the same. Fig. 3 is a detail perspective view of one of the supporting members, and Fig. 4 is a similar view of a slight modification of said member.

20 The embodiment herein shown of the invention comprises a receptacle, pocket or bag body 1 formed of any suitable material, as, for example, a textile fabric. The pocket 1 has a relatively large mouth 2. 25 Two opposite sides of the mouth are hemmed, piped or threaded as shown at 3 to receive the bag-engaging portions of the supporting members 4.

The supporting members 4 are preferably 30 of wire and similar in construction. Each member consists of a suspension loop 5 to engage a supporting hook A, a straight supporting rod 6 for holding the pocket, and a locking device 7. The rods 6 are suffi- 35 ciently long so that the mouth 2 of the pocket may be made of the desired size. The loop 5 may be of any suitable design, being preferably, however, in the form of a triangle. The locking device 7 consists of

40 a U-shape bend or hook 8 at one end of the extended loop 5 adapted to receive one end of the rod 6. The weight of the pocket upon this supporting rod serves to keep the end of it seated in the bend 8. If desired, 45 the rod 6 may be offset as shown at *a* in Fig. 4, to form a protecting shoulder for the hem. The supporting members may also be suitably covered in any desirable manner as shown at *b*.

50 The supporting members 4 are adapted to

be suspended side by side upon the hook A, with the locking devices 7 at opposite sides of the pocket.

When anything is to be put in the pocket, the outside supporting member 4 is removed 55 from the hook A and the mouth 2 enlarged by drawing the released supporting member away from the hook. The other member 4 on the hook A now not only supports the pocket, but also participates in holding 60 the mouth 2 distended. To close the pocket, the released supporting member is returned to the hook. To remove the pocket 1 from the supporting members 4 for cleaning or washing it, the rods 6 are removed from the 65 hooks 8 and withdrawn from the hems 3.

It will be seen that the supports 4 are readily detachable from the pocket, insure a large opening, and can be cheaply and easily constructed.

I claim as my invention:

1. A bag having, in combination, a pocket having two hems at opposite sides of the mouth, and two triangular supporting members, each member comprising a triangular loop, a straight pocket-engaging rod integral with one end of and extending across said loop and threaded through one of the hems, and a hook integral with the other end of said loop and adapted to removably support the free end of said rod. 70

2. A bag having, in combination, a pocket having two hems at opposite sides of the mouth, and two supporting members each comprising a loop, a pocket-engaging rod, 75 and a catch adapted to removably support said pocket-engaging rod, said rods being threaded through said hems.

3. A bag having, in combination, a pocket having an open end and provided with devices along opposite edge portions at said end adapted to be engaged by supporting members, and two wholly separate and independent supporting members, each comprising a suspending loop adapted to engage 90 and depend from a support, and a straight rod attached at one end to said suspending loop and supported at its other end by means of a hook on the opposite side of said loop, the two rods passing through said de- 95 100

vices at opposite edge portions of the bag and the bag being arranged to be opened by removing only one of said supporting members from its support and drawing said member away from the other supporting member.

In testimony whereof, I hereunto set my hand.

FRANK X. SANDT.
In the presence of—
W. M. BURKE,
PETER F. TACKI.
